UNITED STATES PATENT OFFICE.

BALDWIN S. MOORE, OF AUSTIN, TEXAS.

PROPELLED VEHICLES.

SPECIFICATION forming part of Letters Patent No. 293,347, dated February 12, 1884.

Application filed May 26, 1883. (No model.)

To all whom it may concern:

Be it known that I, BALDWIN S. MOORE, of Austin, county of Travis, Texas, have invented certain new and useful Improvements in Means for Propelling Vehicles, of which the following is a specification.

The essential feature of my invention resides in the combination, with the vehicle, of an extensible frame adapted to freely slide back and forth on the vehicle, and when in use to bear below upon the ground, road, or track over which the vehicle is to move, and above upon or against the vehicle. When under these conditions the frame is extended, it bears against the ground and pushes up against the vehicle. The effect of this would be to lift the vehicle; but this tendency, owing to the sliding connection between the two, is translated into a sliding movement of the one on the other.

20 The manner in which my invention is or may be carried into effect can best be understood with reference to the accompanying drawings, in which—

Figure 1 is a side elevation of a three-wheel vehicle embodying my invention. Fig. 2 is a plan of the same. Fig. 3 is a detailed view, hereinafter referred to. Fig. 4 is a sectional side elevation, on an enlarged scale, of one of the propellers. Fig. 5 is an end elevation, partly in section, of the same. Fig. 6 is a plan view, on an enlarged scale, of that portion of the apparatus which contains the mechanism for reversing the movement of the vehicle. Fig. 7 is a side elevation, partly in section, of said mechanism. Fig. 8 is a sectional side elevation, on an enlarged scale, of the devices by which the one or the other of the two sets of cranks with which the propeller is provided is coupled to the motor mechanism, according to the direction in which the vehicle is to move.

In the drawings I have shown three of the devices which I term the "propellers." A description of one will answer for all.

45 Each propeller consists of an upper frame, A, carrying friction-rollers B, which are supported and adapted to move in a guideway, C, formed for them on the under side of the vehicle. The propeller can thus move longitudinally with respect to the vehicle. Supported in the frame by one and the same pivot, a, is a pair of levers, b, to whose ends are

pivoted or jointed two similar levers, c, whose lower ends converge and are hung upon a pivot, d, common to both, which pivot is in 55 the upper portion of a standard, D, fixed to A. The pivot-pin d is capable of vertical play, and that end is held in vertical slots d'. The standard D is a divided standard, and has formed in it vertical sockets, which receive 60 the upper ends of rods D', which can slide in those sockets. The rods D' are connected to a base-piece, E, which is attached to an axle, F. On this axle are mounted wheels G, which can revolve thereon. Hung on a common 65 pivot, e, Fig. 4, in the upper part of the standard D, are two lever-arms, f. Their lower ends diverge, and are jointed at f' to similar lever-arms, g, whose lower ends meet, and are hung upon one and the same pivot, h, in the 70 base-piece E. Hung upon the pivot d are two 75 arms, i. One of these arms at its lower end is jointed to a lever, j, pivoted on one of the lever-arms f, and the other arm, i, is similarly connected to the other lever-arm f. From the inner end of each lever j extends an arm, k, which is jointed to said lever at one end, and is formed at the other end with a beam-piece, k', which overhangs and bears upon the end of that lever-arm f, to which it is applied beyond the pivot f'.

Under the arrangement thus far described it will be seen that if the extensible frame formed by the two pairs of levers b and c be elongated vertically the result will be to push 85 the pivot-pin d down in its slot. This movement of the pivot-pin will correspondingly force downward the arms i, with the effect of vibrating the lever j in a direction to cause the bearing-pieces k' to press upon the ends of levers f, and to thus vertically elongate the 90 extensible frame formed by the two pairs of levers f and g, this extension of the frame being permitted by the sliding connection between D and D'. Inasmuch as the propeller 95 bears at the top against the vehicle and at the bottom against the ground, the effect of the vertical extension of the propeller-frame would be to lift the vehicle, were it not for the sliding connection between it and the vehicle; but by reason of this sliding connection the movement of parts, which will naturally follow the path of least resistance, will take place in the direction permitted by the sliding connection,

so that the vehicle will move longitudinally with respect to the propeller. In order to lock the ground-wheels g of the propeller against rotary movement at this time, I connect the 5 base E to the axle F by a bolt, L , which has a slight up-and-down play through the axle, and I interpose between the base and axle a spring, m , which normally keeps the base in its uppermost position. On the inner faces of the 10 ground-wheel I form annular shoulders or hubs n , and on the rods D' , I put bearing pieces or shoes n' , which overhang said hub, so that when the propeller-frame is extended the rods D' may be pushed down far enough 15 to cause the shoes n' to bear tightly upon the hubs n , and thus lock the ground-wheel in place.

In order to impart the requisite movement to the propeller, I make use of a drum, H , 20 mounted in the frame A , and extending through the frame formed by the two upper pairs of levers, b and c . The drum is connected by chains o to the points where the levers b and c are jointed together, and it is provided with 25 one or more cranks, p , by oscillating which the drum can be turned in one or the other direction, as desired. The effect of turning it in one direction will be to elongate the propeller-frame, and in the other direction to shorten 30 said frame. The crank p is connected by rod p' to a vibratory lever, p'' , on the front of a vehicle, which, by connecting-rod p'' , is connected to a crank-shaft, p^4 , adapted to be rotated by hand. When the crank-shaft is rotated, it 35 serves to elongate and shorten the propeller-frame alternately, and also to draw the propeller-frame in a direction to bring it back in position after each stroke.

In the arrangement shown in the drawings 40 I use three propellers. The two outer ones move in unison, while the intermediate one acts alternately with them.

In order to enable the propeller at the commencement of each stroke to take a firm hold 45 on the ground, I provide an automatic retarding device, (shown more plainly in Fig. 3,) consisting of a spring-catch, r , which, when the frame A of the propeller is drawn forward, rides over and engages a pin, r' , on the frame, 50 and thus holds the frame long enough to permit the propeller at the commencement of the work to take a firm hold on the ground.

I come now to the description of mechanism by which the direction of movement of the 55 vehicle can be reversed. For this purpose I make the drum H in three parts—the central part, H , and the two side or end parts, H' . The two end parts, H' , are secured upon a sleeve, H'' ; the central part, H , is secured upon 60 a shaft, H^3 , extending through the sleeve, which latter, as shown in Figs. 5 and 6, is cut away, so as to admit of the attachment of the center part to the shaft, and also of the requisite independent rocking movement of these 65 parts. The two side parts, H' , are connected to the lever-frame b and c by one set of chains,

o , and the center part, H , is connected to said lever part by another and independent set of chains. One set of cranks, p , is connected to the sleeve H'' , and another set, p^5 , is connected 70 to the shaft H^3 . These two sets of cranks are placed quartering to one another, so that the one set will operate in a contrary direction to the other set. Thus the propeller will be elongated when at the front or at the rear of the 75 guideway in which it moves, according to which set of cranks it is operated by. Cranks p are connected to a yoke, 1, which passes through a longitudinal slot, t , in the connecting-rod p' , and cranks p^5 are connected to a 80 yoke, 2, which passes through a slot, t' , in said connecting-rod. (See Fig. 8.) With each yoke is combined a locking-pin, 3 and 4, so arranged that when the one yoke is locked by its pin to the connecting-rod p the other yoke is unlocked 85 and free to slide back and forth in its slot. The locking-pin for the one yoke is situated at the end of the slot of that yoke, opposite to the end of the slot for the other yoke at which the other locking-pin is located. Locking-pin 3 is provided with a disk contained in 90 a guide shell or cylinder, 5, and is normally pressed upward by a spring, 6, out of engagement with its yoke. Above the disk or head of this pin is a cylinder, 7, containing a piston, 8, whose rod 9 bears down upon the head of the pin. The other locking-pin, 4, is provided with a head, down upon which bears a spring, 10, which presses the pin down in a direction to engage its yoke. Beneath the 95 head of this pin are cylinders 11, containing pistons whose piston-rods bear upwardly against the under side of the head of the pin.

Connected with the cylinders 7 and 11 by pipes 12 is a liquid-containing cylinder, 13, 100 containing a piston, from which extends a rod, 14, which can be depressed by a treadle or other suitable pressing device, 15, on the vehicle. The position normally occupied by the parts is represented in Figs. 7 and 8; the pin 105 3 is out of engagement with its yoke, and the pin 4 is engaged with its yoke. If it be desired to reverse the position of the parts, the rod 14 is depressed by the treadle 15. By this means the liquid is forced out from the 110 cylinder 13 into cylinders 7 and 11. Consequently the piston-rod of cylinder 7 will push down the locking-pin 3 in engagement with its yoke, and the piston-rod of cylinder 11 will at the same time lift the locking-pin 4 out 115 of engagement with its yoke, and the parts will occupy this change of position so long as the treadle is depressed.

Having now described my invention and the manner in which the same is or may be carried into effect, what I claim, and desire to secure by Letters Patent, is—

1. The combination of the vehicle, the vertically-extensible propeller-frame connected thereto, so that the one may slide longitudinally upon the other, and arranged so that when elongated it will bear above against the 120 125 130

vehicle and below upon the ground, and mechanism for causing the elongation and sliding movement of the said propeller-frame, these parts being combined and having the mode of operation substantially as hereinbefore set forth.

2. The combination, with the vehicle, the vertically-extensible propeller-frame carried by and sliding lengthwise on said vehicle, and the propeller-actuating mechanism, of reversing mechanism, substantially as described, whereby the direction of movement of the ve-

hicle upon the propeller-frame at the time the latter is elongated or extended by its actuating mechanism can be reversed at will, substantially as and for the purposes hereinbefore set forth.

In testimony whereof I have hereunto set my hand this 14th day of May, 1883.
